GAME

Clyde W. May, Lancaster, Pa., assignor to Grey Iron Casting Company, Mount Joy, Pa., a corporation of Pennsylvania

Application July 16, 1940, Serial No. 345,704

4 Claims. (Cl. 35—69)

The present invention relates to games and more particularly to a game of jackstones and to improved jackstones for use therein.

Ordinary jackstones, commonly referred to as "jacks," comprise six-legged articles that may be easily picked up from a surface onto which they are thrown during the playing of the game. The game of jackstones is widely played by young children and is performed by throwing a number of jackstones, usually five or six, onto a smooth surface; the jackstones are then picked up either singly or in groups to the accompaniment of a bouncing ball. The old and well-known game offers amusement to children.

The present invention aims to provide a game having the amusement features of jackstones and in addition having educational features which teach a child characters such as numerals and letters of the alphabet, and also addition, subtraction, multiplication, spelling, et cetera. Thus a child may learn these while playing the popular game of jackstones. These additional characteristics make the present game desirable for use in kindergartens and other elementary classes for young children. The individual jackstones of the present invention easily cast and are constructed to permit a child to pick them up with ease either singly or in groups.

An object of the present invention is to provide a new educational and entertaining game.

Another object of the invention is to provide a game adapted to teach children the appearance of numerals and of the letters of the alphabet.

Another object of the invention is to teach children addition, subtraction, multiplication and spelling.

A further object of the invention is to provide an improved jackstone having advantages over known jackstones.

Other and further objects of the invention will be obvious upon an understanding of the illustrative embodiment about to be described, or will be indicated in the appended claims, and various advantages not referred to herein will occur to one skilled in the art upon emloyment of the invention in practice.

A preferred embodiment of the invention has been chosen for purposes of illustration and description and is shown in the accompanying drawing, forming a part of the specification wherein:

Figs. 1 to 9 inclusive are perspective views of a preferred embodiment of the invention;

Fig. 10 is an elevational view of the structure illustrated in Fig. 3;

Figs. 11 and 12 illustrate modified forms of the invention; and

Fig. 13 illustrates a still further modification of the invention.

Referring again to the drawing, and more particularly to Figs. 1 to 8, there is shown a set of jackstones, each jackstone comprising a main body portion 1 having outwardly extending supporting members 2. The characters in Figs. 1 to 8 are in the shape of the numbers 1 to 9 inclusive. The digital characters 9 and 6 are similar but are preferably of a different color so as to facilitate distinguishing them from each other. The main body portions 1 of the characters are preferably rounded, lie substantially in a single plane and may be easily read. They may be formed with configurations conforming to any suitable style of type.

The supporting members 2 serve to hold the characters in various elevated or raised positions so that they will not lie flat and so that they may be readily picked up either separately or in groups during the playing of a game. The supporting members 2 of each character preferably extend outwardly from a point adjacent the central or mid-portions of the character, the supporting members being preferably two in number and located at opposite sides of the character. In the preferred embodiment of the invention each of the supporting members is shown as having a length equal to about one-half the height of a character. It has been found that this proportion of the characters and supporting members provides jackstones which, when tossed on to a floor or other surface, will readily tumble and roll about into numerous diverse combinations. The present characters cannot lie flat regardless of the positions in which they may fall; the configurations of the main body portions are readily discernible and they may be easily picked up.

Various rules may be promulgated for playing the present game. For example, players may be required to pick up characters in a certain sequence or to pick up characters which add up to give totals. The players may also be required to pick up characters and subtract them from a certain given figure. If desired, a character in the shape of a multiplication sign, "X", may be included for playing games involving multiplication. The possible variations are numerous.

In Fig. 9 the invention is shown embodied in a jackstone having a main body portion 4 in the shape of a letter of the alphabet. Supporting members 5 similar to those described in con-

nection with the several characters of Figs. 1 to 8 extend outwardly from opposite sides of the alphabetical character and serve the same function as described in connection with the digital characters. The letter "A" has been chosen to illustrate generally the application of the invention to main body portions in the shape of letters of the alphabet. It will be clear that the invention may be embodied in letters of the alphabet other than those shown.

Many types of games may be played with the present jackstones which are in the shape of letters of the alphabet, all depending upon the imagination and the ingenuity of the players, for example, the spelling out of words, addition, subtraction and multiplication. If desired, a game may be played which includes both numerals and letters.

Figs. 11 and 12 illustrate modifications of the invention wherein jackstones in the shape of numeral or letter characters 7 and 8, respectively, have supporting members 10 and 11 positioned adjacent the ends of the characters instead of adjacent the centers of gravity or mid-portions thereof. The supporting members 10 have been shown as located adjacent the top of the numeral of Fig. 11 and the supporting members 11 as adjacent the bottom of the letter in Fig. 12, but it is to be understood that the supporting members or prongs 10 and 11 may be located adjacent opposite ends of the respective characters. Jackstones embodying the features of Figs. 11 or 12 function similarly to those of the preferred embodiment.

In Fig. 13 there is shown a jackstone 13 having at opposite sides thereof supporting members or prongs 14 and 15 similar to those described in connection with the preferred embodiment. The prongs 14 and 15 of this figure are not positioned immediately opposite each other, but are located adjacent opposite ends of the character body. One of the prongs is located adjacent the top and at one side of the character body, and the other prong is located adjacent the bottom and at the opposite side of the character body. The features of this modified form of the invention are shown applied to a character body in the shape of a numeral, but they are equally applicable to characters in the shape of letters of the alphabet.

It will be seen that the present invention provides a new and improved jackstone which is simple and inexpensive to manufacture and sell. The present jackstones are educational as well as entertaining. Their cost is no greater than present types of jackstones which will enable children to obtain the educational advantages afforded without extra cost and at the same time to add to the entertaining features of the game. The game encourages children to learn the appearance of numerals and letters and also may be used to teach them the principles of addition, subtraction and spelling. Also, when not playing jackstones the numbers and letters can also be used for spelling, addition and subtraction by laying them side by side. The supporting members hold the letters and numbers in an ideal position for this purpose.

As various changes may be made in the form,

construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. A set of jackstones for teaching characters to be used in a game of the class described, comprising a plurality of jackstones having body portions provided with a plurality of integral projections lying in a plane and said body portions being in the configuration of different characters respectively and also having a plurality of integral projections extending outwardly from the planes of the respective characters at opposite sides thereof whereby the body portions having the configurations of characters are adapted to be supported at an angle to a surface upon which the jackstones are thrown.
- 10 2. A set of jackstones for teaching letters of the alphabet to be used in a game of the class described, comprising a plurality of jackstones having body portions including a plurality of integral projections lying in a plane and said body portions being in the configuration of different letters of the alphabet respectively and also having a plurality of integral projections extending outwardly from the planes of the respective letters at opposite sides thereof whereby the body portions having the configuration of letters are adapted to be supported at an angle to a surface upon which the jackstones are thrown.
- 20 3. A set of jackstones for teaching numerals to be used in a game of the class described, comprising a plurality of jackstones having body portions including a plurality of integral projections lying in a plane and said body portions being in the configuration of different numerals respectively and also having a plurality of integral projections extending outwardly from the planes of the respective numerals at opposite sides thereof whereby the body portions having the configuration of numerals are adapted to be supported at an angle to a surface upon which the jackstones are thrown.
- 30 4. A set of jackstones for teaching characters adapted to be used in a game of the class described comprising a plurality of jackstones having body portions provided with a plurality of integral projections lying in a plane and said body portions being in the configuration of characters respectively, such as letters and numerals discernible from opposite sides thereof and also having a plurality of integral projections extending outwardly substantially perpendicularly to the planes of said characters at opposite sides thereof with the bases of said projections being substantially at the centers of gravity of the characters and the height thereof being about one-half the height of the character integral therewith, whereby the body portions having the configuration of the characters are adapted to be supported at an angle to a surface upon which the jackstones are thrown so that the nature of the particular character may be easily ascertained regardless of the position of the jackstone.
- 40 5. A set of jackstones for teaching numerals to be used in a game of the class described, comprising a plurality of jackstones having body portions including a plurality of integral projections lying in a plane and said body portions being in the configuration of different numerals respectively and also having a plurality of integral projections extending outwardly from the planes of the respective numerals at opposite sides thereof whereby the body portions having the configuration of numerals are adapted to be supported at an angle to a surface upon which the jackstones are thrown.
- 50 6. A set of jackstones for teaching characters adapted to be used in a game of the class described comprising a plurality of jackstones having body portions provided with a plurality of integral projections lying in a plane and said body portions being in the configuration of characters respectively, such as letters and numerals discernible from opposite sides thereof and also having a plurality of integral projections extending outwardly substantially perpendicularly to the planes of said characters at opposite sides thereof with the bases of said projections being substantially at the centers of gravity of the characters and the height thereof being about one-half the height of the character integral therewith, whereby the body portions having the configuration of the characters are adapted to be supported at an angle to a surface upon which the jackstones are thrown so that the nature of the particular character may be easily ascertained regardless of the position of the jackstone.
- 60 7. A set of jackstones for teaching numerals to be used in a game of the class described, comprising a plurality of jackstones having body portions including a plurality of integral projections lying in a plane and said body portions being in the configuration of different numerals respectively and also having a plurality of integral projections extending outwardly from the planes of the respective numerals at opposite sides thereof whereby the body portions having the configuration of numerals are adapted to be supported at an angle to a surface upon which the jackstones are thrown.
- 70 8. A set of jackstones for teaching characters adapted to be used in a game of the class described comprising a plurality of jackstones having body portions provided with a plurality of integral projections lying in a plane and said body portions being in the configuration of characters respectively, such as letters and numerals discernible from opposite sides thereof and also having a plurality of integral projections extending outwardly substantially perpendicularly to the planes of said characters at opposite sides thereof with the bases of said projections being substantially at the centers of gravity of the characters and the height thereof being about one-half the height of the character integral therewith, whereby the body portions having the configuration of the characters are adapted to be supported at an angle to a surface upon which the jackstones are thrown so that the nature of the particular character may be easily ascertained regardless of the position of the jackstone.
- 80 9. A set of jackstones for teaching numerals to be used in a game of the class described, comprising a plurality of jackstones having body portions including a plurality of integral projections lying in a plane and said body portions being in the configuration of different numerals respectively and also having a plurality of integral projections extending outwardly from the planes of the respective numerals at opposite sides thereof whereby the body portions having the configuration of numerals are adapted to be supported at an angle to a surface upon which the jackstones are thrown.
- 90 10. A set of jackstones for teaching characters adapted to be used in a game of the class described comprising a plurality of jackstones having body portions provided with a plurality of integral projections lying in a plane and said body portions being in the configuration of characters respectively, such as letters and numerals discernible from opposite sides thereof and also having a plurality of integral projections extending outwardly substantially perpendicularly to the planes of said characters at opposite sides thereof with the bases of said projections being substantially at the centers of gravity of the characters and the height thereof being about one-half the height of the character integral therewith, whereby the body portions having the configuration of the characters are adapted to be supported at an angle to a surface upon which the jackstones are thrown so that the nature of the particular character may be easily ascertained regardless of the position of the jackstone.

CLYDE W. MAY.
